[57] CLAIM

The ornamental design for a combined lens and tracking indicator light for a personal security alarm, as shown and described.

DESCRIPTION

FIG. 1 is a perspective view of a combined lens and tracking indicator light for a personal security alarm showing my new design;

FIG. 2 is a top plan view thereof, with the bottom being flat and unornamented;

FIG. 3 is a front elevation thereof; the rear elevation being a mirror image; and,

FIG. 4 is a right side elevation thereof; the left side elevation being a mirror image.

*Fig. 1**Fig. 2**Fig. 3**Fig. 4*
